Assignor to

Frederick A. Sheldon and Chauncy C. Green of same place, Sellers Patent No. 2437. Dated Sept. 25, 1866.

Design for a Cook's Stove.

The Stove referred to in the Sellers Patent and making part of the same,

To all whom it may concern:

Be it known that James R. Heyde of the City of Troy in the County of Rensselaer and State of New York have invented and produced a new Design for Cook's Stoves of which the following is a full, clear, and exact description, reference being had to the accompanying photographic drawings in which,

Fig. 1. is a diagonal view

Fig. 2. a side view, and,

Fig. 3. a front view, all of a cooking stove embodying my said

Design. The parts being marked by the same letters in all the figures

The distinguishing feature of the design of the legs or feet of the cooking stove, shown by the aforesaid photographic drawings is the formation and arrangement of a leaf a, on the lower part and of a central piece b, and lateral curved check work panels c, on the convex upper portion of said leg or foot, so as to appear as shown by the aforesaid photographs.

The distinguishing feature of the design of the side plates of the stove represented by the aforesaid photographs, is the horizontal stuffed edge, diamond inclosing check work band D, on the lower portion of the side plates. The upright plaid check panel E, diamond E, rounded top F, and concave angular sides and bottom G, on the front portion of the side plates; and the horizontal plaid check ground H, with scalloped lower edge, on the upper portion of the side plates; all shaped and arranged so as to appear as represented by Fig. 1. and 2. of the aforesaid photographs.

DES. 2437

2. The distinguishing feature in the design of each of the oven doors of the cooking stove shown by the annexed photographs is, the rectangular plaid check panel (c), having a central rosette (E), and a surrounding ornamental moulding (I), all shaped and arranged so as to appear as shown by Figs. 1. and 2. of the aforesaid photographs.

The distinguishing feature in the design of the front plate of the cooking stove shown by the aforesaid photograph, is the two way plaid check ground (J, J), bearing a letteroid scroll (K), all shaped and arranged so as to appear as represented by Figs. 1. and 3. of the aforesaid photographs.

And the distinguishing feature in the design of the front doors of the cooking stove shown by the annexed photograph is a plaid check, rectangular panel (I), bearing an ornamental moulding (M), and a circular centre piece (N), all shaped and arranged so as to appear as shown by Figs. 3. and 4. of the aforesaid photographs.

What I claim as my invention or production, and desire to secure by Letters Patent is. — The Design for cooking stoves herein set forth & shown.

In testimony whereof, I have unto set my hand this 31st day of July 1866.

Witness.

Austin S. Park,
Frederick Smith.
